DESCRIPTION

U.S. PATENT DOCUMENTS

FIG. 1 is a front perspective view of the adjustable vehicle backseat organizer with pockets shown in an open position; FIG. 2 is a front perspective view of an adjustable vehicle backseat organizer with pockets shown in folded closed position;

FIG. 3 is a front elevation view of FIG. 2;

FIG. 4 is a back elevation view of FIG. 2;

FIG. 5 is a top plan view of FIG. 2;

FIG. 6 is another top plan view of FIG. 2;

FIG. 7 is a right elevation view of FIG. 1; and,

FIG. 8 is a left elevation view of FIG. 1.

The broken lines showing of portions of the adjustable vehicle backseat organizer with pockets is included for the purpose of illustrating environmental structure and no part of the claimed design.
